UNITED STATES PATENT OFFICE.

ROBERT W. MOTISHER, OF SEWELL, NEW JERSEY.

DUMP CAR.

Application filed August 6, 1927. Serial No. 211,186.

This invention relates to improvements in hopper cars, and more particularly to the dumping mechanism.

Heretofore hopper cars, used for transporting coal, sand, gravel and similar materials, have been provided with doors of various types, designed to be opened when the lading is to be unloaded. Such doors open by gravity and when in the closed position serve to partially support the weight of the material. They are held in closed position by various conventional locking mechanism. The disadvantage of such structures is that the locking mechanism is subjected to great strains and if these are broken or displaced from locking position, by the jars due to transit, an appreciable loss of lading results.

It is an object of my invention to provide a door for a hopper car which closes by gravity.

Another object of my invention is to provide a car of this character in which the weight of the lading is utilized to maintain the hopper door in closed position.

A further object is to provide a hopper door so designed as to reduce lading losses to a minimum.

Yet another object is to provide an effective operating mechanism for a hopper door and a simple and positive locking means therefor.

With these and other equally important objects in view, the invention comprehends the provision of a hopper and a coacting door of arcuate shape adapted to close by gravity, with which is associated a rugged and effective operating mechanism.

To facilitate an understanding of the invention, I have shown in the accompanying drawings, by way of example, a device which embodies its underlying principles. In these the same reference numerals refer to similar parts throughout the several views, of which

Figure 1 is a side view, partly in section and partly in elevation, of a hopper car embodying the invention;

Fig. 2 is a plan view of the device shown in Fig. 1;

Fig. 3 is a cross section taken on the line 3-3 of Fig. 1;

Fig. 4 is an enlarged detail view of the operating mechanism and its associated locking means.

There is shown in the drawings a car 1 supported in a conventional manner, through the intermediacy of journals and axles, upon the flanged wheels 2. The car is provided

with longitudinal frame members 3 and side supports 4 in the usual manner. To the frames and supports are riveted, or otherwise suitably secured, plates 5 which form the car body. Attached to the frame pieces are the bottom plates 6. As shown, particularly in Fig. 1, these are mounted at an angle to the horizontal so as to present an inclined surface to facilitate discharge of the load in the manner well understood.

As shown in Figs. 1 and 3, there is provided an arcuate plate forming the bottom of the car adjacent the hopper. At its peripheral edges this plate member is extended angularly, as at 8, to present L-shaped securing flanges. These flanges may be riveted, welded, or otherwise suitably attached to the adjacent side plates of the car body. As will be seen from an inspection of Fig. 1, the arcuate hopper plate is substantially quadrantal in circumferential length and its ends terminate some distance from the subjacent ends of the inclined plates 6. By reason of this construction a space is permitted, at the end of 80 the chute 6, for the egress of the lading.

There are provided curved door plate members which cooperate with the hopper bottom and the chutes to close off the discharge ends of the chutes and retain the lading within 85 the car. These doors comprise essentially arcuate plates 9 conforming in curvature to the hopper plate 7. Rigidly secured to the under side of the door plates are a plurality of truss members 10. Adjacent the plate 90 these are provided with curved terminal flanges 11 adapted to rest flatly against the plates. These members may be rigidly attached together by rivets, spot welds, or any other convenient means. At their other ends 95 the truss members 10 may be joined and provided at the juncture or apex with an elongated collar 12.

The doors 9 are mounted on a car body for oscillating movement in such a manner as to 100 close or open either chute opening at the option of the operator. To accomplish this purpose the side members of the car are extended downwardly as at 13. At the lower portion the extensions are drawn out at 14 105 and apertured so as to provide elongated bushings. These bushings are adapted to receive the terminal ends of a supporting shaft 15. The collars 12, of the truss members 10, are keyed to the shaft 15 so 110 as to rotate therewith. It will be appreciated that the door plates 9 are firmly

supported from the car frame and may swing with the shaft 15. It is to be understood that in lieu of extending the sides of the car to serve as a support for the truss shaft any other method may be employed; thus the ends of the shaft may be supported in a skeleton framing attached to and depending from the bottom of the car. Likewise the truss members 10 in place of being joined at their contiguous ends may be separately mounted on the shaft.

When the chutes are closed the door plate is in the position shown at the right side of Fig. 1, with its lower end abutting the adjacent edge of the inclined bottom plate 6. It will be seen that the weight of the door plate and its connected truss members 10 tend to rotate these members downwardly and thus act to retain the door in its closed position. It is apparent also that the weight of the lading, bearing downwardly on the curved surface of the door plate, exerts a downward force thereon and thus aids materially in maintaining it in closed position.

When it is desired to discharge the lading from the car the door plates may be moved upwardly. To permit such movement there is provided a simple mechanism adapted to act directly upon the doors to elevate them to the desired position. This comprises rotatable members connected through transmission mechanisms to the door plate. More specifically the elevating means includes a rotatable shaft 16 suitably journaled in support plates 17 affixed to the car body. These plates may be formed with elongated journal bearings to insure smooth rotative movement of the shafts. Intermediate its ends each of the shafts has keyed thereon a plurality of pinion wheels 18. Rigidly secured to the under side of the door plates and co-extensive therewith are segmental racks 19. The pinion gears mesh with the racks in the manner well understood.

As will be noted from an inspection of Fig. 3, the ends of the shafts 16 project some distance beyond the exterior faces of the plates 17. The protruding ends of the shaft are formed with an angled surface 16', to receive a crank or wrench. It will be seen that by means of such a tool either of the shafts may be rotated in the desired direction to open or close the doors. As an example, if it is desired to open the left hand chute (Fig. 1) the shaft 16 is rotated in a clockwise direction. This movement is imparted to the door through the intermediary of the pinion 18 and rack 19. When the tool is removed from the shaft the weight of the door 9 and its associated parts will cause a depression of the door to its closed position.

Since the hopper doors are adapted to close by gravity it is essential that means be provided to retain them in elevated position during the period of unloading. A typical con-

struction accomplishing this result is shown in detail in Fig. 4. This comprises a ratchet wheel 20 and an associated pawl 21 cooperating with each end of each shaft. The ratchet wheel may be keyed to the shaft 16 so as to 70 rotate therewith. The pawl 21 is freely pivoted upon a stud 22 so as to be swung to the two positions shown by full and broken lines in Fig. 4. At its free end each pawl is formed with a laterally shouldered head portion 23 adapted to fit snugly between the serrations upon the periphery of the ratchet wheel.

In a construction of this type it is desirable to insure a positive locking of the door 80 during the unloading of the car. To accomplish this there is provided two locking members operatively associated with each pawl. These comprise essentially the arms 24 freely pivoted upon the pivot pins 25. As shown, 85 the lower ends of the arms are squared. When it is desired to lock the door in any predetermined position, the pawl 21 is swung about its pivot so as to engage the teeth of the ratchet wheel. If it is desired to lock the 90 right hand door (as viewed in Fig. 1) the pawl 21 is moved to the position shown in dotted lines in Fig. 4. After the pawl has engaged the ratchet the locking arm on the left is swung in a clockwise direction about its 95 pivot 25 until the squared end seats in the shoulder formed by the shank and projecting head of the pawl. In this position the pawl is securely locked and movement of the shaft 16 and the hopper door is prevented. If the 100 left hand door (Fig. 1) is to be locked, the pawl 21 is moved to the position shown in full lines in Fig. 4 and the right hand arm 25 is swung in a counterclockwise direction to engage and retain it in locking position.

It will be appreciated that by freely pivoting the pawl and by providing the two locking arms 25, the locking mechanism may be of standard construction and hence can be mounted on either end of each shaft. This 110 interchangeability of parts assures economies of manufacture and replacement. Likewise the door plates 9 and truss members 10 may be made interchangeable.

In Fig. 3 there is shown, diagrammatically, 115 a modified form of the bearing plate 17. It may be found desirable to provide some means for protecting the free ends of the shaft 16 and the associated locking mechanisms. This may readily be done by forming the plate 17 with laterally extending flanges. To simplify the drawings, but a portion of the flange 26 has been shown. It is to be understood, however, that this may extend around the perimeter of the plate and projects at such a distance 120 as to form an open faced casing to protect the parts mentioned.

It will also be appreciated that the portion 125 of the car adjacent the curved door plates 9 may be provided with arcuate channel 130

grooves which receive the edges of the plate and act as guides therefor. It is also manifest that any suitable anti-friction means may be associated with these two parts.

5 The operation of the device will be apparent from the foregoing description. When in normal position the arcuate doors are in their lowermost position and close to ends of the hopper chutes. When the car is 10 to be unloaded the shafts 16 are rotated in the appropriate directions by means of a suitable tool. After the doors have been elevated to their upper limit or to any desired intermediate position, they may be retained there by 15 causing engagement of the pawl with the ratchet wheel. After the desired amount of material has been unloaded the door or doors may be returned to closed position by releasing the pawl. If, for any reason, the doors 20 become jammed so that their weight is not sufficient to effect the closing, the shafts 16 may be positively rotated by again utilizing the crank or wrench. It is to be noted particularly that the two doors are separately operable and that this operation may be performed from either side of the car.

It is to be understood, of course, that the particular construction of the door may be varied to render it suitable for the several 30 types of hopper cars. If the device is to be applied to a car provided with a central longitudinal frame member, each door would be made of two sections. The general principles of construction and mode of operation would, 35 however, obtain with such modifications.

While I have shown and described the preferred embodiment of my invention, it is to be understood that this is merely for the purposes of exemplification, for since its underlying principles may be embodied in other specific mechanical structures, I do not intend to be limited to those shown and described except as such limitations are clearly imposed by the appended claims.

45 I claim:

1. A hopper car comprising side members and an upwardly convex bottom portion, an arcuate door plate juxtaposed to the bottom portion.
- 50 2. A hopper car comprising an upwardly convex bottom portion, a pivotal arcuate door member adjacent the bottom portion adapted to be closed by gravity and means to open the door.
- 55 3. A car comprising side members and a curved bottom portion, a curved door member adjacent the bottom portion, a rack at-

tached to the door and means cooperating with the rack to open the door.

4. A hopper car comprising an arcuate bottom portion, an arcuate door member adjacent the bottom portion and adapted to close by gravity, a rack attached to the door and means engaging the rack to elevate the door. 60

5. In a car of the character described, a door mechanism comprising an upwardly convex member adapted to close by gravity, means to open the door and mechanism operatively associated with said means to lock the door in any predetermined position. 70

6. A car of the character described comprising an upwardly convex bottom portion and an associated curved door member, means to operate the door member from a plurality of positions. 75

7. A hopper car of the class described comprising an arcuate bottom portion, an arcuate door plate adjacent the bottom portion, a rack attached to the plate and means including a rotatable shaft positively connected to the rack to elevate the door. 80

8. A hopper car of the class described comprising an arcuate bottom portion, an arcuate door plate adjacent the bottom portion, a rack fixed to the plate, means to elevate the plate including a rotatable shaft and means to lock the shaft in any predetermined position. 85

9. A hopper car of the class described comprising an arcuate bottom portion, an arcuate door plate adjacent the bottom portion, a rack fixed to the plate, means to elevate the plate including a rotatable shaft, means to lock the shaft comprising a ratchet affixed thereon and an associated pawl. 90

10. A hopper car comprising an upwardly convex bottom portion, an arcuate door plate associated therewith adapted to close by gravity and means to oscillate the door to raise it to open position. 100

11. A hopper car comprising an upwardly convex bottom portion, arcuate door plates associated therewith adapted to be closed by gravity and means to mount the doors for oscillating movement about a single axis. 105

12. In a car of the character described, an arcuate bottom portion, a plurality of optionally operable arcuate door plates mounted so as to close by gravity, a plurality of operating means for each door and means to lock the operating means. 110

In testimony whereof I affix my signature.

ROBERT W. MOTISHER.
